(57) **CLAIM**

We claim the ornamental design for the hand held computer with input device cover, as shown and described.

DESCRIPTION

FIG. 1 is a front elevation view of a hand held computer with input device cover showing the new design.

FIG. 2 is a left side elevation view.

FIG. 3 is a right side elevation view.

FIG. 4 is a rear elevation view.

FIG. 5 is a top plan view; and,

FIG. 6 is a bottom plan view.

The broken line disclosure, for example of the hand held computer display environment, is for illustrative purposes only and forms no part of the claimed design.
